UNITED STATES PATENT OFFICE.

EDMOND HALF, OF PARIS, FRANCE.

DEVICE FOR GIVING WARNING OF FIRE.

Application filed September 18, 1924, Serial No. 738,432, and in France May 10, 1924.

This invention relates to improvements in devices for giving warning of fire, based upon the known principle of the expansion of air contained in a metallic box having very thin walls, the air in expanding operating a mechanical device adapted to close or break an electric circuit, thus operating any kind of alarm signal, such for instance as an electric bell.

10 The present invention refers more particularly to means for eliminating the mechanical devices generally employed up to the present, replacing them by a simple apparatus which functions in a perfect manner.

15 The characteristic features of the apparatus are the following:—

The air contained in the box with metallic walls, or even in a receptacle of glass, porcelain or the like, is caused when expanding to 20 operate directly, with the intervention of a tube placed in an appropriate position, a small piston or other analogous part which when moved closes or opens an electric circuit so as to release or set in motion the alarm 25 signal.

The piston or the like may also operate a needle or some kind of lever mechanism so as to close an electric circuit in connection with the alarm signal.

30 The accompanying drawing shows, by way of example, one method of carrying out the invention.

In the drawings Fig. 1 is an elevation of the whole apparatus, with a portion in section.

Fig. 2 is a part section, to a larger scale 35 showing the device attached to a metallic box, according to a second method of carrying out the invention.

Fig. 3 is also a section of the device illustrating a third method of carrying out the 40 invention.

The device for giving warning of fire comprises in the usual manner a metallic box 1 with thin walls. This box may be round or of any other appropriate shape. The bottom 45 or any other portion thereof may be strengthened or reinforced according to requirement.

Attached to the top plate 2 of the box 1 is a tube 3 in which is adapted to slide a small piston 4. The lower portion of this piston 50 is bevelled off and is adapted to rest on the extremity of a contact screw 5.

The tube may be provided below the piston

with an annular ledge or disc having a perforation 6. This is intended to regulate the 55 quantity of air operating on the piston 4.

The diameter of the piston is slightly less than the inner diameter of the tube 3 so as to leave between the walls a space enabling air to pass in small quantities and to escape to 60 the outside through a perforation 7 formed in the cap at 9, or in some other suitable portion of the tube 3, for instance as shown at 9 in Fig. 3.

The tube is provided with a second contact 65 screw 8.

The operation is as follows. When the surrounding temperature rises steadily, the air in the interior of the reservoir expands. If this expansion of air is rapid, the said air 70 rapidly affects the piston 4, which slides in the tube, and leaving the contact 5 causes the breakage of the circuit which is connected to an alarm bell adapted to be rung when the 75 circuit is broken or in connection with any other suitable alarm.

On the other hand when the increase of temperature is gradual, the expansion of the air contained in the box 1 will also be gradual, and the air will have time to escape between 80 the outside of the piston and the wall of the tube without the piston being operated.

Fig. 2 shows a second constructional embodiment of the invention in which the tube is bent at right angles. In this case the air 85 expansion box is placed at the side and the tube is fixed to a plate 2 at the side thereof.

The apparatus operates in the same manner as already described with reference to Fig. 1.

At Figure 3, the tube in which the piston slides is inclined. Moreover, the piston after 90 sliding causes the closure of a circuit in connection with the alarm means.

For this purpose the upper extremity of the tube is provided with an insulating cap 95 10 with a central contact screw 11.

When the piston 4 is pushed upwards owing to the sudden expansion of the air contained in the box 2, which expansion is caused by a sudden rise in the surrounding temperature, the piston comes into contact with the contact screw 11 and the electric circuit is closed to the alarm device which immediately 100 comes into operation.

It is evident that the piston described can 105 be replaced by any part of any shape which

will fulfil the same object, such for instance as a ball or the like, and that without departing from the principle of the invention.

Moreover, the expansion box can be of any shape, round, hexagonal, oval, truncated or otherwise, permitting expansion and certain operation of the device.

What I claim and desire to secure by Letters Patent of the United States of America

10 is:

1. In a switch adapted to be operated by a sudden rise of temperature, the combination of a reservoir for air having walls with a high coefficient of thermal conductivity, a tube forming a cylinder in connection with the said reservoir, a slideable plug loosely mounted in the said cylinder, and having its lower end bevelled, means for retaining the plug in the said cylinder, means above the
- 15 said plug for allowing air to escape to the outside, and contacts adapted to be operated
- 20

when the plug is moved, substantially as described.

2. In a switch adapted to be operated by a sudden rise of temperature, the combination of a reservoir for air having walls with a high coefficient of thermal conductivity, a tube forming a cylinder in connection with the said reservoir, and formed of electric conducting material, a slideable metal plug loosely mounted in the said cylinder, and having its lower end bevelled, an insulated contact screw passing through the walls of the said cylinder, the inner end of the screw supporting the bevelled end of the plug, another contact screw mounted on the cylinder, means for admitting air to the lower end of the cylinder and means for allowing air to escape from the upper end of the cylinder, substantially as set forth.

In witness whereof I affix my signature.

EDMOND HALF.
